FIG. 1

FIG. 2

UNITED STATES PATENT OFFICE

2,089,464

BLIND FOR OPENINGS

Charles H. Wood, Oakland, Calif.

Application September 9, 1936, Serial No. 99,946

4 Claims. (Cl. 156—17)

This invention relates to blinds of the so-called "Venetian" type used for closing openings such as windows or the like.

The principal object of the invention is to provide a Venetian blind, composed of a plurality of co-acting shutters, in which preselected groups of the shutters may be moved independently of others of the shutters so that fractional portions of the opening, in which the blind is mounted, may be closed while the other portions of the opening remain uncovered.

Another object of the invention is to provide means, for accomplishing the above result, which may be readily incorporated in existing blind structures without materially altering the latter.

The invention possesses other objects and features of value, some of which, together with the foregoing, will be set forth in detail in the specification hereunto annexed. It is to be understood that the invention is not to be limited to the specific form thereof shown and described as various other embodiments thereof may be employed within the scope of the appended claims.

Referring to the drawing:

Figure 1 is a perspective view of a Venetian blind structure incorporating the improvements of my invention.

Figure 2 is a perspective diagrammatic view showing the arrangement of the control cords.

The greater part of Figure 1 illustrates a conventional Venetian blind structure comprising a support 3 which may be the frame of a window, or a door, in the opening of which the blind is mounted. Secured to the upper portion of the frame, within the opening, by screws, or otherwise, is a header 4 provided at opposite ends with brackets 6 on which is supported for rotary movement about its longitudinal axis, a rocker bar 7. Attached to opposite edges of the rocker bar, in spaced relation, is a pair of fabric tapes 8 depending from the bar to form loops and provided at spaced intervals with connecting webs 9 upon which rest the shutters 11. It will be seen that the spacing of the webs 9, along the fabric loops, determines the spacing of the shutters. Secured in the lower end of each of the loops is a bar 12 which acts as a weight to maintain the tapes 8 taut. One of the brackets 6 encloses suitable gearing, not shown, which may be actuated by pull chains 13 to cause rotation of the rocker bar 7 and consequently cause the opposed tapes 8 of each loop to move in opposite directions thereby moving the shutters 11 into over-lapped positions, similar to that in which the

group of shutters in the lower portion of Figure 1 is shown, to cover the window or door opening. Each of the shutters 11 and the rocker bar 7 are provided with aligned apertures 14 through which pass cords 16 the lower end of each of which is secured to the bar 12 and the upper portions thereof passing into the header 4 through apertures 17 and outwardly therefrom through apertures 18 located adjacent one side of the frame 3 and terminating together in a connector 19. It will be seen that by pulling downwardly on the connector 19 the bar 12 will be moved toward the upper part of the frame thereby collapsing the blind and uncovering the greater part of the opening to permit passage of the maximum amount of light therethrough.

The structure and the operation thus far described will be recognized as the conventional Venetian blind in which the shutters 11 may, by the pull chains 13, be moved, as a group, to positions wherein they are disposed edgewise and thereby provide the least degree of obstruction to light coming through the opening, or to positions wherein they are broadside to the light thereby covering the opening and permitting the passage therethrough of a minimum of light. I have provided means whereby separate groups of the shutters may be opened or closed independently of the other groups thereby permitting the covering or uncovering of as little or as great a portion of the area of the opening as desired. Secured to the underside of the rocker bar 7 is a pair of spaced staples 21, or their equivalent, which provide guides for control cords 22. The arrangement of the control cords may be more readily understood by reference to Figure 2 of the drawing. It will be seen that each of the control cords is double, the right hand set comprising the lead 22 which passes through the right hand staple 21 and downwardly therefrom to connect with the forward edge of the shutter 11, an aperture 23 being provided in the shutter to facilitate the connection of the cord by means of the knot 24. The other lead 26 of the pair passes through the right hand staple 21 across and through the left hand staple and downwardly to be joined with the forward edge of the shutter in the same manner as the lead 22 is connected. The left hand control cord comprises a lead 27 which passes through the left hand staple and downwardly to connect with the rear edge of the shutter, and a lead 28, which, after passing through the left hand staple crosses over and passes through the right hand staple and thence downwardly to be secured to the rear edge of

the shutter. It will be seen that since the leads of each pair are tied together by the knot 29, a downward pull on either of the control cords 31 will cause the pair of leads connected thereto to move in unison, movement of the left hand cord causing the rear edge of the shutter to rise, and movement of the right hand control cord causing the forward edge of the shutter to rise. When one edge of the shutter rises the opposite edge will of course drop under the influence of gravity, the degree of drop being limited, in proportion to the height that the opposite edge is raised, by the webs 8. As many of the shutters as desired may be connected together for actuation by the control cords 31 simply by extending the respective leads to connect with successive shutters as indicated by the cords 32.

In Figure 1, I have shown two groups of shutters, the upper group being controlled, as explained above, by the cords which pass through the guides 21 secured to the rocker bar 7, and the lower group being controlled by a similar arrangement of cords which pass through staple guides 33 secured to the underside of the bottom shutter of the upper group. It will be evident of course that the total number of shutters may be divided into as many groups as desired merely by providing additional sets of control cords for each additional group and connecting the respective shutters of each group together.

From the foregoing description it will be seen that I have provided simple and effective means whereby the positioning of selected groups of the shutters comprising a blind may be instantly varied either to deflect the light entering the opening upwardly or downwardly into the room and whereby portions of the area of the opening may be closed off to the exclusion of other portions of the area. It will also be seen that the operation of one set of control cords will not affect the setting of another group of the shutters, and that being so simple, the repairing or replacing of the control cords, should they require it, is within the province of the house-keeper who possesses an ordinary degree of skill.

I claim:

1. In combination with a closure for an opening comprising a plurality of shutters, means for moving said shutters unitarily to cover and uncover said opening, means connected with a group of said shutters for moving said group independently of said first shutter moving means to cover and uncover a portion of said opening, and means connected with another group of said shutters for moving said second group independently of said first shutter moving means and the moving means for said first group to cover and uncover an additional portion of said opening.

2. In combination with a closure for an opening comprising a plurality of parallel shutters disposed within said opening, means connected with all of said shutters for moving said shutters about their longitudinal axes to cover and uncover said opening, means connected with a group of said shutters and operable independently of said first moving means for moving said shutters of said group about their longitudinal axes to cover and uncover a portion of said opening, and means connecting another group of said shutters together for moving said shutters of said second group about their longitudinal axes, independently of said first moving means and the moving means of said first group, to cover and uncover another portion of said opening, said moving means for said second group being supported by a shutter of said first group.

3. In combination with a closure for an opening comprising a plurality of shutters of sheet material supported in spaced superposed relation in said opening, and means for moving said shutters about their longitudinal axes into overlapped relation to cover said opening, means for moving a group of said shutters independently of said first-mentioned moving means comprising a pair of connected cords slidably supported by one of said shutters, and connected with overlying edges of each shutter of said group whereby when said cords are moved said edges of the shutters will be elevated above the opposite edges thereof.

4. In combination with a closure for an opening comprising a plurality of shutters of sheet material supported in spaced superposed relation in said opening, and means for moving said shutters about their longitudinal axes into overlapped relation to cover said opening, means for moving a group of said shutters about their longitudinal axes in one direction, independently of said first-mentioned moving means comprising a pair of connected cords slidably supported by one of said shutters and connected with overlying edges of each shutter of said group whereby when said cords are moved said edges of the shutters will be elevated above the opposite edges thereof, and means for moving said group of shutters about their longitudinal axes in the other direction independently of said first-mentioned moving means, comprising a pair of connected cords slidably engaging the supports for said first cords and connected with the overlying opposite edges of each shutter of said group whereby when said second cords are moved said edges of the shutters will be elevated above said first-mentioned edges thereof.

CHARLES H. WOOD.
